UNITED STATES PATENT OFFICE.

CLAYTON C. HARTING, OF WOODSTOCK, ILLINOIS, ASSIGNOR TO THE OLIVER TYPE-WRITER COMPANY, OF CHICAGO, ILLINOIS, A CORPORATION OF ILLINOIS.

TYPE-WRITING MACHINE.

1,115,669.

Specification of Letters Patent.

Patented Nov. 3, 1914.

Application filed January 21, 1914. Serial No. 813,374.

To all whom it may concern:

Be it known that I, CLAYTON C. HARTING, a citizen of the United States, and a resident of Woodstock, in the county of McHenry and State of Illinois, have invented certain new and useful Improvements in Type-Writing Machines; and I do hereby declare that the following is a full, clear, and exact description thereof, reference being had to the accompanying drawings, and to the letters of reference marked thereon, which form a part of this specification.

This invention relates to an improved device for releasing the carriage of a typewriting machine from its letter spacing mechanism, whereby the carriage may be moved freely in either direction from end to end of its travel, for the purpose of facilitating the insertion of characters in an already printed line, or for other purposes.

The device constituting my invention involves substantial improvements in carriage release mechanism of the form shown in U. S. Letters Patent to Ingersoll, No. 837,569 December 4, 1906.

My improvements are shown as applied to an "Oliver" typewriting machine, wherein endwise movement of the carriage, for letter spacing, under the action of its actuating spring, is effected through the medium of an escapement mechanism embracing a rotative pinion which is yieldingly held in intermeshing relation with a rack-bar on the carriage frame and means for disengaging said carriage from the escapement mechanism, embracing a release bar adapted to force said pinion out of mesh with the rack-bar.

A mechanism constructed according to the features of my invention may, however, be applied to other typewriting machines having similar means for effecting letter spacing.

My invention consists in the matters herein described, more particularly pointed out in the appended claims and fully illustrated in the accompanying drawings, in which—

Figure 1 is a view in front elevation of the carriage of an Oliver typewriting machine; Fig. 2 is a view in horizontal section, taken on line 2—2 of Fig. 3, with portions broken away to show the carriage release device; Fig. 3 is a view in transverse, vertical section of the carriage and portions of the ma-

chine frame, showing parts of the operating mechanism.

Referring to the drawings, the endwise movable carriage 10 is supported upon the carriage shift-frame 11 of the machine (Fig. 3) by means comprising a roller 12 which engages a horizontal rail 13, extending longitudinally of said shift-frame. The carriage supports the rotative platen 14, provided at its ends with turning knobs 15, 15, located exterior to the ends of the carriage, in the usual manner. The letter spacing mechanism of the machine, as illustrated, comprises features as follows: A rack-bar 16 forms the lower, front, longitudinal member of the carriage; said rack-bar being provided at its forward edge with rack-teeth, which are located below, and project a short distance forwardly from, the platen 14. A vertical shaft 17, journaled in suitable bearings on the shift-frame 11, is provided at its upper end with a pinion 18, adapted to engage the teeth on said rack-bar and to be thrown out of engagement therewith by means of the release device, as hereinafter described. As herein shown, the shaft 17 is rotatively mounted at its upper end in a block 19, adapted to slide toward and from the rack-bar within a guide slot in a forwardly projecting bracket 20 on the shift-frame. A spring 21, mounted within said slot, acts to yieldingly force the block toward the rack-bar. The lower end of the shaft is mounted upon the shift-frame, in such a manner as to permit the upper end of said shaft to oscillate toward and from the rack-bar. An escapement wheel (not shown), mounted upon the lower portion of the shaft and operatively connected to the letter spacing mechanism of the machine, forms part of the escape-mechanism which controls the rotative movement of the shaft.

Referring now to the means for actuating the shaft 17, for throwing the pinion 18 forwardly out of mesh with the rack-bar 16, a release bar 24 is longitudinally arranged upon an upwardly facing, horizontal bearing surface of the said rack-bar 16. Said release bar is similar in construction to that shown in the prior U. S. Letters Patent to Oliver, No. 599,863, and Ingersoll, No. 837,569, and is adapted to move or slide on the rack-bar in a direction toward and from the shaft. As illustrated in the drawings, said

release bar consists of a flat metal plate slightly tapering toward its ends and provided at its forward margin with an upright flange 25, adapted to engage a roller 26 mounted at the upper end of the shaft 17 immediately above the pinion 18. Said flange is preferably formed by bending upwardly the forward marginal portion of the bar. Adjacent to the ends of the release bar are provided two parallel slots 27, 27, arranged obliquely with reference to the forward margin of the bar. These slots engage headed screws or studs 28, 28, extending therethrough and fixed in the rack-bar, said 15 studs acting to hold said release bar in position and to guide the same so that it has an oblique movement on the rack-bar. The margins of the bar adjacent to the said slots 27 are curved rearwardly, thereby forming 20 projections 27^a, 27^b, within which the rear parts of said slots are formed.

At the left side of the carriage is an actuating rod 29, the same comprising a flat metal strip having sliding engagement with 25 the flat top bearing surface of the rack-bar and arranged parallel with the release bar slightly in the rear of its forward margin. Said rod 29 extends laterally beyond the carriage and passes through a guide slot 30 formed in the adjacent side plate 30 of said carriage. At the outer end of the rod is provided a knob 31 adapted to be pressed by the finger of the operator to effect the inward endwise movement of the rod. The 35 inner end portion of the rod is enlarged and provided with a longitudinal guide slot 32 having engagement with a stud or screw 33 inserted in the rack-bar. The end of the said rod 29 abuts against a bearing shoulder 24^a, on the release bar, which faces toward the left at the left-hand side of the projection 27^a. When the rod 29 is pressed inwardly, the release-bar is moved toward the right by the pressure of the said rod on the 40 transverse shoulder 24^a and an oblique movement is given to the release-bar by the action of the guide slots 27, 27 on the studs 28, 28, whereby the release-bar is shifted forwardly; the end of the rod sliding on the shoulder 24^a as the release-bar 24 moves forwardly.

At the opposite right-hand end of the carriage, the release-bar is provided with an actuating device performing the same function as the actuating device at the left-hand end of the carriage, but embracing a combination of levers operating as a compound lever. As illustrated, these levers are two in number. One of the levers 35 is pivoted 55 upon the carriage in the rear of and inwardly from the end of the release-bar, by means of a pivot-stud 36, inserted in the rack-bar and extending through the lever intermediate of its ends, thereby forming two 60 arms 37 and 38. The left-hand or longer

arm 37 is curved and partially embraces a rearward projection 27^b of the release-bar, in which is formed the rear part of the right-hand slot 27, and engages the left-hand and rearward part of the margin of 70 said projection so as to act thereon in a direction forwardly and to the right, when the said arm 37 is swung forwardly. The right-hand arm 38 of the lever is made of U-shape and is provided at its outer end 75 with a short bearing surface 39. The other lever 40 of the compound lever is pivoted to the rack-bar at the right of the lever 38 and adjacent to the end of the release-bar. This lever is pivoted on the rack-bar so as 80 to swing in a horizontal plane, by a pivot stud 41 located intermediate of its ends. The longer or right-hand arm 42 of the lever 40 projects outwardly through a slot in the adjacent side plate of the carriage and 85 beyond the same, said arm being suitably formed to provide a finger-piece having a rearwardly facing surface, adapted to receive the pressure of the operator's finger in manipulating the actuating device. The 90 inner or left-hand arm 43 of the lever 40 extends toward the lever 35 and constantly engages the front face of the arm 38 thereof. By exerting a pressure in a forward direction upon the outer end of the arm 42, the 95 inner arm of said lever 40 is swung rearwardly, so as to press the arm 38 of the lever 35 rearwardly, while its left-hand arm is swung forwardly. By reason of the pivot 100 of the lever 35 being located at the rear of the release-bar, the left-hand end of said lever 35 has an oblique movement, in the direction of the oblique movement of the release-bar, and acts to press said release-bar forwardly and toward the right. 105

At the central part of the release-bar is attached one end of a coiled spring 44, the opposite end of said spring being fixed to the carriage and at such point that the axis of the spring substantially coincides with the direction of movement of the release-bar. As shown in the drawings, the rear margin of the release-bar is provided with a hooked projection 45 preferably formed integral with the bar, and to which the end of the 110 spring may easily be attached. The function of the spring is to draw the release-bar rearwardly to its non-operative position when the pressure on either of the actuating devices is released. These actuating devices 115 are provided at both ends of the carriage to permit the release-bar to be operated by either hand of the operator and are designed to be readily and easily accessible to the hand of the operator when grasping either 120 of the knobs of the platen for the purpose of turning the platen, or for shifting the carriage from left to right. The left-hand actuating device, embracing the endwise 125 movable rod, enables the operator, in press- 130

ing on the rod, to shift the carriage to the right while simultaneously operating the release-bar to release the escapement mechanism from the rack-bar. This feature is 5 fully set forth in the prior U. S. Letters Patent to Ingersoll and hence does not constitute a part of the present invention. The right-hand actuating device made as described, however, has advantages over the 10 corresponding device shown in the said patent to Ingersoll, as will appear from the following. In the prior device, the lever handle, corresponding to the lever arm 42 in my present invention, was moved rearwardly 15 to operate the release-bar, and to so operate the device it was necessary for the operator to use the thumb for this purpose. In shifting the carriage with the right hand, the natural manner in doing so is to grasp the 20 right-hand platen knob with the thumb and index finger, and to also utilize the thumb for operating the release-bar involves an unnatural position of the hand. Moreover, when the thumb is used to press the right-hand release lever backwardly, the thumb and hand are brought in position for contact 25 with parts of the machine forward of the carriage, as the latter is moved toward the left, but when the release lever is arranged 30 to be operated by the finger, as herein described, the fingers and thumb may pass behind the parts in front of the carriage, without liability of striking the parts referred to.

In my device the lever arm 42 is shifted 35 forwardly toward the operator to operate the release-bar. Thus when the platen knob is grasped by the right hand in the most natural manner, the second finger may be easily and conveniently employed in manipulating the release-bar without shifting the 40 position of the hand upon the platen knob, and without liability of injuring the hand by its contact with the parts at the right side of the machine, in the rapid movement 45 of the carriage toward the left.

A further advantage gained by the construction described in the right-hand release device, is that the release-bar may be thereby more smoothly and easily thrown forward 50 against the action of its retracting spring, because of the fact that the lever arm which directly engages the release-bar, acts thereon in an oblique direction and substantially in the direction of movement of the 55 release-bar.

The features of the device embodied in my invention may be modified in the details of construction without departing from the spirit of my invention, and for that 60 reason I do not wish to be limited to the particular details of construction illustrated and described, except in so far as specifically pointed out in the appended claims.

I claim as my invention:

65 1. The combination with a carriage rack-

bar, a pinion, a platen mounted on the carriage, of a release bar on and having horizontal movement transversely of the carriage, means acting on the release-bar to move the same transversely backward, and 70 means for actuating said release-bar transversely forward, comprising a lever pivoted on said carriage and having an arm which extends to the left of its pivotal axis and acts on the release bar in a direction to 75 move the same forward, and a second lever pivoted on the carriage and having an outer arm extending outwardly from the adjacent end of the carriage, and an inner arm adapted to act rearwardly on the right-hand arm 80 of the first mentioned lever.

2. The combination with a carriage rack-bar, a pinion, a platen mounted on the carriage, of a release-bar having horizontal movement on the carriage endwise and transversely in an oblique path, means acting on the release-bar to move the same endwise and transversely backward, and means for actuating said release-bar endwise and transversely forward, comprising a rearward projection on the release-bar having a bearing surface facing rearwardly and to the left, a lever pivoted on said carriage and provided with two arms, one of said arms acting on said bearing surface in a direction 90 forwardly and to the right, and means adapted to act rearwardly on the other arm of said lever.

3. The combination with a carriage rack-bar, a pinion, a platen mounted on the carriage and having turning knobs at both ends of the carriage, of a release-bar having horizontal movement on the carriage endwise and transversely in an oblique path, a retracting spring acting on the release-bar to move the same endwise and transversely backward, and means for actuating said release-bar endwise and transversely forward, comprising a lever pivoted on said carriage, and having an arm which extends to the left 100 of its pivotal axis and acts on the release-bar in a direction forwardly and to the right, and a second lever pivoted on said carriage and having an outer arm extending outwardly from the end of the carriage adjacent to the platen turning knob at the right-hand end of the carriage and an inner arm adapted to act rearwardly on the right-hand arm of the first mentioned lever.

4. The combination with a carriage rack-bar, a pinion, a platen mounted on the carriage and having turning knobs at both ends of the carriage, of a release-bar having horizontal movement on the carriage endwise and transversely in an oblique path, a retracting spring acting on the release-bar to move the same endwise and transversely backward, and means for actuating said release-bar endwise and transversely forward, comprising a rearward pro- 120 125 130

jection on the release-bar having a bearing surface facing rearwardly and to the left, a lever pivoted on said carriage and provided with two arms, one of said arms extending to the right of the pivotal axis of the lever and the other of said arms extending to the left of said pivotal axis and acting on said bearing surface in a direction forwardly and to the right, and a second lever pivoted on said carriage and provided with an outer arm extending outwardly from the right-hand end of the car-

riage adjacent to the platen turning knob at that end of the carriage, and an inner arm adapted to act rearwardly on the right-hand 15 arm of the first mentioned lever.

In testimony, that I claim the foregoing as my invention I affix my signature in the presence of two witnesses, this 19th day of January, A. D. 1914.
